CLAIM

I claim the ornamental design for a latch with recessed handle swing zone, substantially as shown and described.

DESCRIPTION

FIG. 1 is a perspective view of the latch with recessed handle swing zone;

FIG. 2 is a top view of the FIG. 1 latch;

FIG. 3 is a front view of the FIG. 1 latch;

FIG. 4 is a bottom elevational view of the FIG. 1 latch;

FIG. 5 is a rear view of the FIG. 1 latch;

FIG. 6 is a left side view of the FIG. 1 latch; and,

FIG. 7 is a right side view of the FIG. 1 latch.
